[57] **CLAIM**

The ornamental design for a molding for furniture, as shown and described.

DESCRIPTION

FIG. 1 is a pictorial view showing a molding for furniture, according to this invention;

FIG. 2 is a front elevational view of the molding;

FIG. 3 is an end elevational view of the molding;

FIG. 4 is a side edge elevational view of the molding;

FIG. 5 is another side edge elevational view of the molding; and,

FIG. 6 is a rear elevational view of the molding.

The molding is shown broken away at the center to indicate indeterminate length.
